UNITED STATES PATENT OFFICE.

CHARLES A. SMITH AND HERBERT L. HILLYARD, OF INDEPENDENCE, KANSAS, ASSIGNEES TO THE NATIONAL SASH AND DOOR COMPANY, OF INDEPENDENCE, KANSAS, A CORPORATION OF KANSAS.

CAPPING HORSE.

Application filed February 28, 1925. Serial No. 12,214.

To all whom it may concern:

Be it known that we, CHARLES A. SMITH and HERBERT L. HILLYARD, citizens of the United States, residing at Independence, in the county of Montgomery and State of Kansas, have invented a new and useful Capping Horse, of which the following is a specification.

In the production of glass cylinders, as a preliminary to the production of window glass, the cylinders or "rollers" unavoidably vary from true cylinders, both in diameter and axis. Such cylinders are most conveniently laid horizontally as a preliminary to being cut into sections and the object of the present invention is to provide a support or capping horse upon which the freshly drawn cylinder may be laid and so uniformly supported that the cylinder as a whole, and the several sections as produced, will be properly supported in such manner as to avoid breakage both before and after the cutting operations.

The accompanying drawings illustrate my invention. In the drawings Fig. 1 is a side elevation of the horse; Fig. 2 a side elevation in partial vertical section, and on a larger scale, of the receiving end of the horse; Fig. 3 a vertical section on line 3—3 of Fig. 2; Fig. 4 a side elevation of the middle portion of the horse; Fig. 5 a fragmentary side elevation, on an enlarged scale and with some parts broken away, at the point "X" Fig. 2; Fig. 6 a fragmentary side elevation on an enlarged scale with some parts broken away at the point "Y" Fig. 2; Fig. 7 a section on line 7—7 of Fig. 6; Fig. 8 a fragmentary side elevation, in partial vertical section, at the point "Z" Fig. 4; and Fig. 9 a section on line 9 of Fig. 8.

In the drawings 10, 10 indicate a pair of base blocks or fulcrum blocks upon each of which is fulcrumed a beam 11, the two beams 11, 11 being arranged in alignment and with their adjacent ends slightly separated as indicated in Fig. 4. Each beam 11 is provided at each side, at an intermediate point, nearer its outer end than its inner end, with a depending plate 12 overlapping the subjacent block 10. Extending between each pair of plates 12, beneath beam 11, is a fulcrum pin 13 which rests upon the upper surface of the subjacent block 10. Each plate 12 is provided with a slot 14 through which a

headed screw 15 is projected into the adjacent block 10. Each pin 13 thus forms a fulcrum support for its beam 11 upon a block 10. Rigidly secured to one end of one of beams 11 at each side is a plate 16, each of said plates overlapping the adjacent end of the companion beam 11 and provided with a slot 17, in its overlapping portion, through which a bolt or lag screw 18 is driven into the companion beam 11, the arrangement being such that the adjacent ends of beams 11 may together swing up or down, the slot 17 permitting the unavoidable approach and separation of the adjacent ends of said beams 11, 11.

The upper edges of plates 16 project above the upper faces of beams 11 and extending between said plates is a pivot bolt 19 upon which an intermediate beam 21 is balanced, or substantially balanced.

Fulcrumed upon the outer ends of beams 11 are intermediate beams 21^a and 21^b, each of which is provided at each side, at its middle, with a depending plate 22 between which is extended a fulcrum pin 23 resting upon the subjacent beam 11, the plates 22 overlapping down over the sides of beams 11 and provided near their lower ends with a slot 24 through each of which is projected a headed screw 25 into beam 11. Depending from the inner end of each beam 21^a and 21^b is a finger 26 which overlaps the side of beam 11 and is provided with a slot 27 through which a headed screw 28 is projected into beam 11.

Balanced upon the opposite ends of each beam 21, 21^a and 21^b, is a roller-section carrier 29, each of which has a length approximating the length of the sections into which the glass roller is to be cut. Each carrier 29 is provided, at or near its middle, at each side, with a depending plate 30 extending down and overlapping the adjacent beam 21, 21^a or 21^b, respectively, a fulcrum pin 31 extending between the plates beneath the carrier and resting upon the beam, each depending end being provided with a slot 32 (Fig. 5) through which a headed screw 33 is projected into the adjacent beam.

Longitudinally slidable on the upper face of each carrier 29 are roller cradles 34 conveniently formed of asbestos webbing supported on a cross-bar 35 which, in turn, is supported by two slides 36, 36 (Fig. 3)

which lie upon opposite sides of the intermediate portion 37 of the carrier 29, and rest upon the side ribs 38 of said carrier, the arrangement being such that the cradles 34 5 may be readily shifted longitudinally of the carriers 29.

Swing of the end carriers 29 on the beams 21^a and 21^b, respectively is limited by a headed screw 39 projected up through the 10 adjacent beam into the carrier, as shown in Fig. 2.

Depending from each end of each of the intermediate carriers 29 is a ratchet bar 45 adapted to cooperate with a fixed pawl 46 15 appropriately placed upon the subjacent beam 11 and the several ratchet bars 45 are connected by links 47 and normally urged towards their pawls by spring 48 (Fig. 1). An operating rod 49, connected to one of the 20 ratchet bars 45, is provided with an operating handle 50 by which the ratchet bars may be readily shifted and this handle 50 may be hooked over a pin 51 (Fig. 2) in order to hold the ratchet bars out of engagement 25 with their pawls.

Depending from one of the beams 11, near its end, is a ratchet bar 52 connected by links 53, 53 with adjacent ratchet bars 45, and arranged to coact with this ratchet bar 52 is 30 a pawl 54 mounted upon a block 55 arranged beneath the adjacent ends of beams 11.

It will be noted that the carriers 29 are interconnected in pairs by means of the intermediate beams 21, 21^a or 21^b so as to 35 swing together about the fulcrum 23 but, at the same time, are capable of independent swing about their individual fulcrums 31. It will also be noted that deflection of either beam 11, by reason of a load applied thereto, 40 will cause an equal but opposite deflection of the aligned beam 11.

The construction described is such that the several carriers 29 have an interrelated 45 flexibility of such character that the supports 29 will either automatically accommodate themselves, or can be made to accommodate themselves, to the various portions of any roller laid thereon in such manner as to form, ultimately, a rigid support for all 50 sections of the roller so that when the roller is cut into successive portions each of the successively cut portions will be independently supported in such manner as to insure 55 against the possibility of a rubbing contact between the adjacent ends of said sections.

In operation, a roller having been drawn, 60 it is taken down by swinging its lower or hole end outwardly and upwardly and lowering its inner or cap end, separating the blow pipe from the drawing cage, and shifting the roller lengthwise to a position above the horse and lowering the roller upon the horse, the roller at this time being supported 65 with its hole end somewhat higher than the

cap end so that the cap end will first come down upon the left hand (Fig. 1) carrier 29, whereupon this carrier will yield downwardly, the left hand end of the left hand beam 11 also yielding downwardly around its fulcrum 13, its right hand or inner end at the same time swinging upwardly and moving beam 17 and the carriers 29 carried thereby upwardly. The adjacent or left hand end of the left hand beam 11 also swings upwardly, by reason of its flexible connection with the adjacent end of the left hand beam 11 so that the right hand beam 11 swings about its fulcrum 13. The intermediate carriers 29 thus rise, under the applied load of the cap end of the roller, to meet the down-coming intermediate portion of the roller and as this load is applied the various carriers 29 yield under the applied load and adjust themselves approximately, and some times entirely, to the irregularities of the roller so that it is well supported throughout its entire length as it finally comes to rest upon the horse. The operator then releases handle 50 from pin 51 so that the several ratchet bars 45 and 52 may coact with their associated pawls. 70 The operator may then, by shifting the cradles 34 lengthwise of the carriers 29, and by vertically adjusting either end of any one of the carriers 29, finally bring them into 75 proper supporting association with the roller throughout its entire length, the several carriers being at that time rigidly locked in place by their several ratchets so that the entire structure becomes substantially a rigid support for the roller throughout its length. The operator may, if it is found necessary, 80 insert some wedges (not shown) between beams 11 and block 55 to obtain the desired 85 stiffness of the structure as a whole.

The removal of the cap from the roller produces no disturbance but when the first cut from the cap is made the freshly produced section supported by the left hand section support 29 swings automatically away 90 from the remaining portion of the roller, owing to the fact that the fulcrum 31 of this section is preferably placed a little to the right of the metal of the support so that the outer or left hand end of the support will 95 swing downwardly to the limit permitted by the screw 39.

As successive sections are cut from the roller, at points between the cradles of adjacent supports 29, each section will remain in 100 vertical position, and there will be no tendency for the freshly cut section to shift relative to the remaining portion of the roller, because each carrier is locked in place and the superjacent portion of the roller is properly supported by the carrier before the cutting operation is accomplished. After a section has been cut the operator may, if he desires, shift the freshly cut section axially 105 away from the remaining portion of the roll. 110

er by sliding the cradles 34 on their carrier 29.

In Fig. 4 we show, as a slight modification, a link 60 attached at one end to one carrier 29 and connected at its other end to the adjacent end of the adjacent carrier 29 by a pin and slot connection 61 so that these adjacent ends will move up or down simultaneously, thus serving to steady the carriers as the glass cylinder is cut into sections. It will be understood that these links 60 may be distributed along the horse.

We claim as our invention:

1. A capping horse for glass cylinders comprising a plurality of carriers arranged in a longitudinal series and each capable of supporting a segregated cylinder section, a transverse fulcrum for each carrier, and a series of fulcrumed beams each supporting a plurality of said transverse fulcrums.

2. A capping horse for glass cylinders comprising a plurality of carriers arranged in a longitudinal series and each capable of supporting a segregated cylinder section, a transverse fulcrum for each carrier, a series of fulcrumed beams each supporting a plurality of said transverse fulcrums, and means for temporarily locking some of said carriers against movement on their fulcrums.

3. A capping horse for glass cylinders comprising a plurality of carriers arranged in a longitudinal series and each capable of supporting a segregated cylinder section, each of said carriers having two longitudinally-shiftable cradles, a transverse fulcrum for each carrier, and a series of fulcrumed beams each supporting a plurality of said transverse fulcrums.

4. A capping horse for glass cylinders comprising a plurality of carriers arranged in a longitudinal series and each capable of supporting a segregated cylinder section, each of said carriers having two longitudinally-shiftable cradles, a transverse fulcrum for each carrier, a series of fulcrumed beams each supporting a plurality of said transverse fulcrums, and means for temporarily locking some of said carriers against movement on their fulcrums.

5. A capping horse for glass cylinders, comprising a pair of aligned base beams each provided with a supporting fulcrum at a point intermediate its length, a connection between the adjacent ends of said beams permitting concurrent vertical movement of said ends, a plurality of intermediate beams, two fulcrumed upon the outer ends of said base beams, respectively, and one fulcrumed upon the inner end of one of said base beams, and a plurality of aligned carriers one fulcrumed upon each end of each of said intermediate beams.

6. A capping horse for glass cylinders, comprising a pair of aligned base beams each provided with a supporting fulcrum

at a point intermediate its length, a connection between the adjacent ends of said beams permitting concurrent vertical movement of said ends, a plurality of intermediate beams, two fulcrumed upon the outer ends of said base beams, respectively, and one fulcrumed upon the inner end of one of said base beams, a plurality of aligned carriers one fulcrumed upon each end of each of said intermediate beams, and means for temporarily locking some of said carriers against movement on their fulcrums.

7. A capping horse for glass cylinders, comprising a pair of aligned base beams each provided with a supporting fulcrum at a point intermediate its length, a connection between the adjacent ends of said beams permitting concurrent vertical movement of said ends, a plurality of intermediate beams, two fulcrumed upon the outer ends of said base beams, respectively, and one fulcrumed upon the inner end of one of said base beams, a plurality of aligned carriers one fulcrumed upon each end of each of said intermediate beams, and means for temporarily locking some of said carriers to the subjacent base beam against movement on their fulcrums.

8. A capping horse for glass cylinders, comprising a pair of aligned base beams each provided with a supporting fulcrum at a point intermediate its length, a connection between the adjacent ends of said beams permitting concurrent vertical movement of said ends, a plurality of intermediate beams, two fulcrumed upon the outer ends of said base beams, respectively, and one fulcrumed upon the inner end of one of said base beams, and a plurality of aligned carriers one fulcrumed upon each end of each of said intermediate beams.

9. A capping horse for glass cylinders, comprising a pair of aligned base beams each provided with a supporting fulcrum at a point intermediate its length, a connection between the adjacent ends of said beams permitting concurrent vertical movement of said ends, a plurality of intermediate beams, two fulcrumed upon the outer ends of said base beams respectively, and one fulcrumed upon the inner end of one of said base beams, a plurality of aligned carriers one fulcrumed upon each end of each of said intermediate beams, each of said carriers having two longitudinally-shiftable cradles, and means for temporarily locking some of said carriers to the subjacent base beams against movement on the fulcrums.

10. A capping horse for glass cylinders, comprising a pair of aligned base beams each provided with a supporting fulcrum at a point intermediate its length, a connection between the adjacent ends of said beams permitting concurrent vertical movement of said ends, a plurality of intermediate beams, two fulcrumed upon the outer ends of said

- base beams, respectively, and one fulcrumed upon the inner end of one of said base beams, a plurality of aligned carriers one fulcrumed upon each end of each of said intermediate beams, each of said carriers having two longitudinally-shiftable cradles and means for temporarily locking some of said carriers against movement on their fulcrums. 45
- 10 11. A capping horse for glass cylinders, comprising a base-beam structure having two fulcrum supports at separated points intermediate its length and a portion intermediate the fulcrums vertically flexible whereby a load applied downwardly to one end of the beam-structure outside a fulcrum will flex upwardly the portion of the beam-structure between the fulcrums, a plurality of intermediate beams, two fulcrumed on the outer ends of the base-beam and one fulcrumed upon the base-beam between its fulcrums, and a plurality of aligned carriers one fulcrumed upon each end of each of said intermediate beams. 50
- 15 12. A capping horse for glass cylinders, comprising a base-beam structure having two fulcrum supports at separated points intermediate its length and a portion intermediate the fulcrums vertically flexible whereby a load applied downwardly to one end of the beam-structure outside a fulcrum will flex upwardly the portion of the beam-structure between the fulcrums, a plurality of intermediate beams, two fulcrumed on the outer ends of the base-beam and one fulcrumed upon the base-beam between its fulcrums, and a plurality of aligned carriers one fulcrumed upon each end of each of said intermediate beams. 55
- 20 13. A capping horse for glass cylinders, comprising a base-beam structure having two fulcrum supports at separated points intermediate its length and a portion intermediate the fulcrums vertically flexible whereby a load applied downwardly to one end of the beam-structure outside a fulcrum will flex upwardly the portion of the beam-structure between the fulcrums, a plurality of intermediate beams, two fulcrumed on the outer ends of the base-beam and one fulcrumed upon the base-beam between its fulcrums, and a plurality of aligned carriers one fulcrumed upon each end of each of said intermediate beams. 60
- 25 14. A capping horse for glass cylinders, comprising a plurality of carriers arranged in a longitudinal series, and each capable of independently supporting a segregated cylinder section, and an equalizing beam system interconnecting and supporting said carriers vertically yieldable. 65
- 30 15. A capping horse for glass cylinders, comprising a plurality of carriers arranged in a longitudinal series, an equalizing beam system interconnecting and supporting said carriers vertically yieldable, and means for temporarily locking some of said carriers against vertical movement. 70
- 35 16. A capping horse for glass cylinders, comprising a plurality of carriers arranged in a longitudinal series, and each capable of supporting a segregated cylinder section, an equalizing beam system interconnecting and supporting said carriers vertically yieldable, and means for temporarily locking some of said carriers against vertical movement. 75
- 40 17. In witness whereof, we have hereunto set our hands at Independence, Kansas, this 14th day of February, A. D. one thousand nine hundred and twenty-five. 80
13. A capping horse for glass cylinders, comprising a base-beam structure having two fulcrum supports at separated points intermediate its length and a portion intermediate the fulcrums vertically flexible whereby a load applied downwardly to one end of the beam-structure outside a fulcrum will flex upwardly the portion of the beam-structure between the fulcrums, a plurality of intermediate beams, two fulcrumed on the outer ends of the base-beam and one fulcrumed upon the base-beam between its fulcrums, and a plurality of aligned carriers one fulcrumed upon each end of each of said intermediate beams, and means for temporarily locking some of said carriers to the subjacent base-beam against movement on their fulcrums.
18. A capping horse for glass cylinders, comprising a base-beam structure having two fulcrum supports at separated points intermediate its length and a portion intermediate the fulcrums vertically flexible whereby a load applied downwardly to one end of the beam-structure outside a fulcrum will flex upwardly the portion of the beam-structure between the fulcrums, a plurality of intermediate beams, two fulcrumed on the outer ends of the base-beam and one fulcrumed upon the base-beam between its fulcrums, and a plurality of aligned carriers one fulcrumed upon each end of each of said intermediate beams, and means for temporarily locking some of said carriers to the subjacent base-beam against movement on their fulcrums.
